SHEAVE-BLOCK.

1,149,837.

Specification of Letters Patent. Patented Aug. 10, 1915.

Application filed September 19, 1911. Serial No. 650,207.

To all whom it may concern:

Be it known that we, CHARLES B. KING and CLARENCE B. WESTON, citizens of the United States, residing at Marion, in the county of Marion and State of Ohio, have invented certain new and useful Improvements in Sheave-Blocks, of which the following is a specification, reference being had therein to the accompanying drawing.

- 10 This invention relates to sheave blocks and is designed more particularly for use with excavating machinery of the boom and dipper type, although applicable to other uses.
- 15 The object of the invention is to provide a sheave block which will be of a very strong, durable construction and will not be injured or the joints thereof loosened by the hammering which it necessarily receives
- 20 when in service.

To this end it is a further object of the invention to provide a sheave block consisting of two cast metal side pieces which are rigidly connected one to the other and which

25 support the sheave between them.

It is a further object of the invention to provide means for retaining the cable in proper relation to the sheave and for spacing apart and reinforcing the side members; 30 and it is also an object of the invention to provide guards for the sheave which will prevent the same being injured or the cables being twisted or displaced when the sheave is drawn close to the point of the boom.

35 In the accompanying drawings, Figure 1 is a side elevation, partially broken away, of the point of a boom showing our improved sheave block connected therewith; Fig. 2 is a section, taken on the line $\alpha\alpha$ of Fig. 1; Fig. 3 is a detail view of a portion of the sheave block showing the same partially in elevation and partially in section; and Fig. 4 is an edge view of the lower portion of the block.

40 In these drawings we have illustrated one embodiment of our invention and have shown the sheave block as comprising two side members 1, each of which consists of but a single piece of metal and is preferably 45 formed by casting. These side members may be of any suitable shape and are here shown as comprising a body portion substantially circular in shape and of a diameter slightly greater than the diameter of the 50 sheave which is to be supported between

the two side members. This sheave, which is indicated at 2, is journaled on a shaft 3 which is mounted at its ends in the respective side members and preferably has its ends squared to hold the same against rotation. The two side members of the block are spaced apart and rigidly connected one to the other. In the present instance each side member is provided on the lower portion thereof with two inwardly extending flanges 4, the flanges on the two side members being arranged directly opposite one another and adapted to abut when the side members are connected one to the other. This connection is preferably formed by means of bolts 5 which extend through the two side members and rigidly connect the same together. In addition to forming spaces to maintain the two side members of the block in their proper relative positions, 60 these inwardly extending flanges constitute cable guards and serve to prevent the cable from dropping away from the sheave. The upper portions of the side members are connected together by means of a bolt or pin 6 which extends through both of said members and is rigidly connected thereto. This bolt also constitutes the means by which the hoisting cable 7 is connected with the sheave block. To this end the pin 6 has mounted 65 thereon a clevis 8 to which the end of the cable is connected. A short sleeve 9 mounted on the pin 6 holds the cable near one of the side members 1 for a purpose which will 70 hereinafter appear. The thickness of the sheave is, in the present instance, somewhat less than the space between the inner walls of the side members of the block, and, to prevent the cable from dropping between the sheave and the side members each member is provided with an inwardly extending projection 10 which is, in the present instance, in the form of an annular flange of a diameter corresponding substantially to the 75 diameter of the sheave and which extends 80 inwardly to a point near the sheave. The sheave block is provided at its lower end with means for connecting the same to the part to be hoisted which, in the present instance, is the excavating dipper. As here 85 shown this means comprises a pin 11 mounted at its ends in the respective side members 1 and having connected therewith a clevis 12 which, in turn, is connected with the bail 90 of the dipper which is shown at 13 in Fig. 1. 110

When the sheave block is employed in connection with a boom and dipper excavating machine it is supported from the outer end of the boom, which is indicated at 5 14 in Figs. 1 and 2. To this end the point of the boom is provided with twin sheaves 15 mounted on a shaft 16 which, in turn, is mounted in bearing brackets carried by the outer ends or points of the two members 10 constituting the boom.

In the operation of the mechanism the sheave block is not infrequently drawn up against the twin sheaves on the boom. This is liable not only to cause the disarrangement 15 of the cables by twisting or otherwise but also is liable to injure the sheaves. To prevent such injury we have provided each side member of the sheave block with a guard portion, which is here indicated by 20 the reference numeral 17, and which extends some distance beyond the adjacent portion of the sheave, and is adapted to engage a part or parts carried by the boom to maintain the sheave block and the sheave in 25 proper relations to the twin sheaves on the boom and to prevent the sheaves from coming in contact one with the other. In the present construction the boom is provided with two guard wheels 18 which are loosely 30 mounted on the shaft 16 between the sheaves and the respective members of the boom and are adapted to be engaged by the guard portions of the corresponding side members of the sheave block. In order that the contact 35 between these parts may be more certain the guard portions of the block are preferably provided with flanges 19 which form wide contact surfaces. These flanges are, in the present instance, extended downwardly and across the body portions of the 40 side members, as indicated at 20, and constitute reinforcing ribs which add materially to the strength of the side members of the block. With this construction when 45 the sheave block is drawn close to the boom point the guard portions of the sheave blocks will engage the guard wheels on the boom and the sheave blocks will move about the axes of guard wheels until they reach the limit of 50 their movement. The clevis by means of which the end of the cable is connected to the end of the sheave block being arranged close to one side of the sheave block and the sheave of the sheave block being maintained 55 in its proper relation to the sheaves on the boom point, it will be obvious that there can be no twisting of the cable or any displacement thereof.

The boom points which support the shaft 60 16 are subjected to severe strain in the normal operation of the excavating mechanism, and, in order to reinforce the ends of the wooden boom members and impart to the same the necessary strength it has been customary to round off the points of these

members and bend either the top or bottom guard plate about this rounded portion of the boom. This construction involves considerable labor and is, therefore, expensive and is open to other objections. In order to 70 overcome these objections we have provided the points of the boom members with bearing blocks 21 of such a size and shape as to form continuations of the boom members. These bearing blocks are mounted between 75 the armor plates 22 and the top and bottom plates 23 and 24, and, when bolted in position, form a very strong durable support for the shaft 16 and the hoisting mechanism which is carried thereby. 80

The operation of the device has been fully explained in connection with the description of the several parts thereof and it will be apparent that we have provided a very strong and durable sheave block which is 85 simple in its construction and can be manufactured at a relatively low cost; that this sheave block is of such a character that it is not liable to injury by the severe hammering which it receives when in use, this being 90 largely due to the one piece construction of the side members thereof which eliminates all joints in these members. It will also be apparent that the block is of such a character that the cable will be maintained in 95 proper relation to the sheave; and further, that the sheave will not be injured nor the cable twisted when the sheave block is drawn close to the boom.

While we have shown and described the several features of the invention as embodied in a sheave block comprising two cast metal side members it will be obvious that many of these features are applicable to built-up sheave blocks or to sheave blocks of constructions other than that here shown.

Further, we wish it to be understood that we do not desire to be limited to the details of construction shown and described, for obvious modifications will occur to a person skilled in the art.

Having thus fully described our invention, what we claim as new and desire to secure by Letters Patent, is:—

1. A sheave block comprising two side members and means to support a sheave between said side members, each side member having reinforcements extending vertically across the same and projecting below the body portion thereof to form a support for a work attaching device, each member also having inwardly extending flanges arranged along the lower edge thereof on opposite sides of said reinforced portion, the flanges of the two side members being adapted to abut and serve both to space the side members apart and to form cable guards, and means to rigidly connect said side members one to the other with said flanges in their abutting positions.

comprising a sheave block having a projection arranged in ent with and adapted to engage the ery of the respective guard wheels, a pported by said projections, a cable carried by said pin and arranged be- 75 the projections, and a sleeve on the tween the clevis and one of the pro- s to retain said clevis adjacent the of said projections.

estimony whereof, we affix our signa- 80 n presence of two witnesses.
